CARBOY FOR LIQUIDS OR THE LIKE

James K. Wareham, New Kensington, Pa., assignor to
Aluminum Company of America, Pittsburgh, Pa., a cor-
poration of Pennsylvania

Filed May 18, 1959, Ser. No. 55,945

Term of patent 14 years

(Cl. D58—17)

Fig. 1

Fig. 2

Fig. 3

Fig. 1 is a perspective view of a carboy for liquids showing my new design wherein the side not shown is the same as the side shown;

Fig. 2 is a top plan view thereof; and

Fig. 3 is a cross sectional view taken on lines 3—3 of Fig. 2.

I claim:

The ornamental design for a carboy for liquids or the like, substantially as shown and described.
